ILLUMINABLE PANEL FOR VISUAL AID KEYBOARD INSTRUCTION DEVICE

Arthur R. Schmoyer, Falls Church, Va.
(P.O. Box 38, Beallsville, Md.)

Filed June 22, 1964, Ser. No. 80,542

Term of patent 14 years

(Cl. D25—1)

FIGURE 1 is a perspective view of an illuminable panel for visual aid keyboard instruction device, showing my new design.

FIGURE 2 is a front elevational view of the rear face of the panel member, shown in FIGURE 1.

The portions of the design that are shown stippled or lined for color in the drawings are of a contrasting color.

The characteristic feature of my design resides in the combination on a musical instruction panel of the type disclosed of the full length black and white key representation, each white key bearing its staff notation on the upper portion thereof, and each black key having a translucent spot through which the contrastingly colored back stripe is visible when appropriately back-lighted, substantially as shown.

I claim:

The ornamental design for an illuminable panel for visual aid keyboard instruction device, as shown and described.
